UNITED STATES PATENT OFFICE.

GEORGE F. EGAN, OF JERSEY CITY, NEW JERSEY.

DISPLAY DEVICE.

Application filed July 14, 1925. Serial No. 43,547.

The present invention relates to improvements in display devices and has for an object to provide an improved display device which may be suspended from any suitable support.

Another object of the invention is to provide an improved device which may be used in conjunction with shelves upon which goods are displayed in stores, whereby the device will cooperate with the edge of beading of a shelf to hold the device thereon to conspicuously display the price of goods without interfering with the display and with the removal and placement of goods upon the shelves.

Other objects of the invention are to provide for the interchangeability of price cards, to maintain the cost of manufacture of the device low, and to make the device simple and light and of a construction easy to mount upon and remove from shelving.

With the foregoing and other objects in view, the invention will be more fully described hereinafter, and will be more particularly pointed out in the claim appended hereto.

In the drawings, wherein like symbols refer to like or corresponding parts throughout the several views:

Figure 1 is a perspective view of one form of the invention shown as applied to a shelf;

Figure 2 is a plan view thereof on a slightly enlarged scale;

Figure 3 is a section taken on the line 3—3 in Figure 2;

Figure 4 shows a perspective view of a slight modification;

Figure 5 is a front elevation thereof;

Figure 6 is a perspective view of a further modification; and

Figure 7 is a perspective view of a still further modified form of the invention.

Referring more particularly to Figures 1, 2 and 3, 8 designates the body portion of the device which is preferably of thin sheet metal possessing some degree of resiliency. The lower and side edges of the sheet metal, which is substantially rectangular in form, are bent or rolled forwardly upon the sheet providing the confining ledges or flanges 9, 10 and 11. These flanges close at their meeting edges at the lower corners of the holder while the flanges are left open at the top portions providing guides down through

which a card, as 12, may be introduced by a sliding movement until it rests upon the lower shelf 9. The flanges not only provide supporting and confining surfaces for the edge portions of the card 12, but they also extend in front of the card and prevent the falling forward of the card or the removal of the card except in an upward direction.

The body portion 8 is shown as provided with an opening 13 made at a convenient point through which access may be had by the thumb or finger to the back of the card 12 for the purpose of initiating its upward movement. The upper edge of the card may be below the upper edge of the body 70 part 8. By inserting the finger or an instrument in back of the card through the opening 13 the card may be raised to a degree to bring its upper edge within grasping position whereupon it may be simply 75 lifted out of the holder. The opening 13 also renders it unnecessary to touch the face of the card and this will enable the card to be moved out of the device without soiling the face of the card with the hands.

The device may be supported by a shelf indicated at 14, which shelf may be provided with a beading or edge 15 having a slot indicated at 16. The device is shown as provided with a flange 17 extending downwardly from the web or apron 18. This web or apron is preferably a part of the body portion and is shown as bent upwardly at an acute angle. The flange 17 is shown as extending vertically downward from the rear 90 most edge of the apron 18. The apron 18 is shown as arranged on the inclination noted for the purpose of conforming to the inclined upper edge 19 of the beading 15.

The flange 17 is shown as fitting into a 95 groove 16 and supports the device in position. The weight of the device and card will tend to retain the flange 17 in place. The flange 17 is preferably made in two or more sections separated by the substantially triangular space 20. In the case illustrated two such sections are shown with the space 20 intermediate thereof. The sections are flexible and resilient and are more easily bent than if they formed one continuous 105 part. Moreover the individually moving sections may adapt themselves more easily to irregularities in the groove 16. Indeed,

the flange 17 may be made in any number of sections and the end of the flange between 110

two adjoining sections may form substantially a point or tooth, which will give a better hold on the support.

Referring more particularly to Figures 4 and 5 the body part 21 is shown as formed at its lower edge with the shelf and retaining flange 22 but the lateral guides are left off except that on one side a small substantially triangular retaining clip 23 is shown as provided. This retaining clip is with advantage stamped from the sheet metal material and folded about to the position indicated. The apron 18 and flange 17 are the same as in the preceding form of the invention and as a consequence they have been similarly numbered. The card 24 in this case, however, is intended to slide horizontally into the holder and along the shelf 22 and the upper guides 25 and 26 cooperate with the lower shelf 22 in admitting of this movement. The guides 25 are shown as of relatively short length they being cut from the material of the sheet metal adjoining the end portions of the apron 18. The metal is shown as bent outwardly and downwardly into substantially U shape providing channels cooperating with the shelf 22 below. The card is slid toward the left until it strikes and enters the clip 23. It is preferable that the card fit with slight friction in the device to avoid the possibility of its displacement, although the card should yield upon slight pressure.

Referring now to Figure 6 the sheet metal body 27 is shown as provided with a lower supporting shelf and flange 28 while at the side portions are two guide clips 29 and 30. The card is intended to be slid down vertically within these clips until it rests upon the shelf 28. Additional metal along the sides of the device are saved over the first form of the construction and the clips will hold the card edges adequately for some uses. At the top of the device an opening 31 is shown as made. The half circle of the opening 31 from the apron 18 admits the finger downwardly behind the card and the half circle in the body portion admits the finger into contact with the card so that it may be lifted up. The opening 13 is also

shown as provided in case it is desirable to initiate feed through the same.

Now referring to Figure 7 the device here comprises the body part 32 with the lower edge 33 and a single clip 34 at one side. In addition there is shown an upper central clip 35 similar to the clip 34 and being cut out from the metal in the apron 18 and folded downwardly. The card may be slid horizontally from the right toward the left into the lower edge 33 and clip 35 until the same strikes the side clip 34. The card is then arrested in proper position and is held therein until active force is brought to bear in removing it.

If desired the side edges of the flange 17 may extend inwardly at an angle.

While I have illustrated my invention in connection with price cards, devices embodying my invention may be used to display, for instance, photographs, and if desired glass or other transparent material may be held in the device in front of the card, photograph or other article displayed.

It is obvious that various changes and modifications may be made in the details of construction and design of the above specifically described embodiment of this invention without departing from the spirit thereof.

What is claimed is:—

A card display device comprising an upright sheet metal body having an opening, a substantially U-shaped flange bent outwardly and upwardly from the entire lower edge of said body, an apron bent backwardly from the entire upper edge portion of said body and having a downwardly turned flange at its rear free edge, a relatively small clip bent outwardly from one intermediate side portion of the body part and having its tip end extending inwardly at substantially right angles to the body part, and spaced guides cut from the upper corner portions of the body part below the upper edge of the body part and folded outwardly and downwardly to slidably receive a card laterally of the device.

In testimony whereof I affix my signature.
GEORGE F. EGAN.
